UNITED STATES PATENT OFFICE.

WILLIAM W. GRIER, OF HULTON, PENNSYLVANIA.

SIDE-BAR VEHICLE.

SPECIFICATION forming part of Letters Patent No. 240,408, dated April 19, 1881.

Application filed January 6, 1881. (No model.)

To all whom it may concern:

Be it known that I, WILLIAM W. GRIER, of Hulton, in the county of Allegheny and State of Pennsylvania, have invented a new and useful Improvement in Side-Bar Vehicles; and I do hereby declare the following to be a full, clear, and exact description thereof.

My invention relates to the construction of side-bar vehicles; and it consists of such a vehicle having the body connected to the side bars by flat springs, each of equal thickness throughout its length, and composed of one or more tapered leaves.

The springs heretofore used for this purpose have been made very stiff, in order to have sufficient strength to sustain the heavier loads placed upon them. Consequently they yielded but little with a light load, and had a rough action with such a load; but the chief objection was that when these springs were depressed by a heavy load they were too stiff to yield properly and pushed out the side bars, and thereby racked the gear and produced rapid wear. I have discovered that a flat tapered spring has quite sufficient strength to sustain the heavier loads, and at the same time sufficient elasticity to yield without distorting the side bars and running-gear.

To enable others skilled in the art to which my invention appertains to make and use the same, I will now describe it by reference to the accompanying drawings, forming a part of this specification, in which—

Figure 1 is a bottom perspective view of the body, side bars, and axles of a vehicle-gear, showing my improved construction. Fig. 2 is an edge view of the spring and its attachment. Fig. 3 shows a modified form of spring, and Figs. 4 and 5 another modified form of the same; Fig. 6, another form, and Fig. 7 is a sectional view of the fifth-wheel of Fig. 1.

Like letters of reference indicate like parts in each.

The body *a* is of any desired form, and is placed in a rectangular frame consisting of the side bars, *b*, front bolster, *c*, and rear axle. Semi-elliptic springs may be substituted for supporting the side bars.

The fifth-wheel is shown at *d*, and has a saddle-brace, *d'*, a split king-bolt, *d''*, attached by nuts to a circular yoke, *d'''*, turning within a

yoke, *d''*. A center brace, *d'''*, or spring-reach is attached to the fifth-wheel.

The springs *e* are fastened to the side bars *b* by suitable shackles *f*, and to the body by bolts, 55 screws, or rivets *g*. These springs are flat tapered leaves of equal thickness throughout their length, the taper extending from the point of attachment with the body to the point of attachment with the side bars. The increased 60 width gives the requisite strength and increases the elasticity. The springs are first rolled or cut out of a sheet of steel and then bent to the required form. I prefer to make them in one piece extending across the body to the opposite sides and tapered each way from the middle, as shown in Fig. 1, it being merely two springs in one piece. This is the simplest and cheapest form, as it requires the least manipulation.

The form shown by Fig. 3 differs from that shown in Figs. 1 and 2, in that the springs *e'* and *e''* are separate and curved laterally. In this instance the regular taper need extend only to the curve, as shown at *e''*, as I have 75 found that it is not necessary to continue it beyond that point. The curved part may preserve the same width throughout, or taper reversely to its point of attachment to the body, if desired. This makes a very strong spring. 80 It requires more work in manufacture than the spring *e*. It is, like the spring *e*, of equal thickness throughout.

The form shown by Figs. 4 and 5 is similar to that shown in Figs. 1 and 2, except that the 85 springs *e''* are separate and have a return-leaf, *i*, extending outward toward the side bar and then fastened to the body. The springs *e''*, like the springs *e*, are of equal thickness. Like *e''*, they may decrease in width from the angle 90 *k* to its point of attachment to the body. It is very elastic and more especially adapted for light loads. This construction gives a simple, strong, durable, and easy-riding vehicle.

The double spring *e* of Figs. 1 and 2 may be 95 made in separate pieces, one extending to one side and the other to the other side.

Instead of placing the springs directly opposite to each other and having their inner ends fastened to the body at or near the middle, they may be arranged to pass each other and have their inner ends fastened to the body

at or near its opposite side, substantially as shown by the bottom plan, Fig. 6.

A modification of my invention would be to form the spring of two or more parallel leaves 5 of equal length and parallel taper, and having the same attachments, each leaf having an equal thickness throughout its length.

What I claim as my invention, and desire to secure by Letters Patent, is—

10 The combination of the body and side bars of a side-bar vehicle with intermediate springs,

each of which is of equal thickness throughout its length, and is composed of one or more tapered leaves, substantially as and for the purposes described.

15 In testimony whereof I have hereunto set my hand.

WILLIAM W. GRIER.
